METHOD OF AND GAUGE FOR ADJUSTING
AUTOMATIC LOOMSHarold Hoeber, South Dartmouth, Mass., assignor
to Draper Corporation, Hopedale, Mass., a cor-
poration of Maine

Application November 14, 1940, Serial No. 365,719

21 Claims. (Cl. 139—380)

This invention pertains to automatic filling replenishing looms and more particularly relates to methods of and gauges for adjusting the shuttle feeler and picker stick thereof.

As generally constructed automatic filling replenishing looms include a reciprocating lay carrying at each end thereof, at least one shuttle box, and replenishing mechanism including a magazine at one end of the breast beam carrying a number of reserve filling carriers, and suitable actuating mechanism provided to automatically eject a filling carrier from the shuttle and to insert a fresh carrier therein upon the detection of filling absence by the filling detecting device. In looms of this type it is essential that the shuttle be properly positioned in the shuttle box relative to the magazine so that a transfer can be made. The position of the shuttle in the shuttle box is determined by the shuttle feeler and the picker. Accordingly it is essential that the shuttle feeler and picker be adjusted so that when the shuttle comes to rest in the shuttle box it will be in proper position, relative to the magazine, for transfer.

Accordingly it is a principal object of this invention to provide in an automatic filling replenishing loom including a magazine, a lay having a shuttle box thereon, a shuttle feeler, a shuttle and a picker stick, a shuttle position gauge comprising indicating means carried by the magazine and indicating means in the shuttle whereby upon alignment of the indicating means said shuttle will be properly positioned in the shuttle box, relative to the magazine for transfer.

A further object of this invention is the provision of a new and improved method of adjusting the shuttle feeler and picker stick to position the shuttle in the shuttle box in operative relation to the magazine, for transfer.

These and other objects of the invention are accomplished in the construction illustrated on the accompanying drawings, wherein;

Fig. 1 is a plan view of the right hand end of the lay and shuttle box showing parts thereof broken away;

Fig. 2 is a rear view partly in section and with parts thereof broken away of the right hand end of the lay, shuttle box and magazine showing one modification of the gauges of this invention mounted in position for use;

Fig. 3 is a view in perspective of one modification of the shuttle positioning gauge;

Fig. 4 is a view similar to that of Fig. 2 but showing a second modification of the shuttle position gauge;

Fig. 5 is a view similar to that of Fig. 2 but showing a third modification of the shuttle position gauge;

Fig. 6 is a view in perspective of the gauge shown in Fig. 4; and,

Fig. 7 is a view in perspective of the shuttle position gauge shown in Fig. 5.

The drawings show a portion of the right hand end of the lay with the right hand shuttle box and portion of the replenishing mechanism. The other parts and mechanisms of the loom, not shown, may be of any suitable usual construction and form no part of the present invention.

The drawings show part of the right hand end 10 of the lay, including a lay beam 1, picker stick 2, carrying a picker 3, a shuttle feeler indicated generally at 4 and parts of the right hand shuttle box including the front box plate 5, back box plate 6 and floor plate 7. A shuttle 8 is shown 15 in the shuttle box. The shuttle has a spur 9 on one end and a spur 10 on the other end and is provided with a bobbin engaging spring 11.

It is essential to the proper operation of the filling replenishing mechanism that upon transfer 20 the shuttle be in proper position with respect to the magazine. As the position of the shuttle in the shuttle box depends upon the position of the picker stick, the position of the picker stick must be adjusted so that each time the shuttle comes 25 to rest with the spur of the shuttle firmly pressed against the picker, the shuttle will be properly positioned for transfer.

The picker stick 2 oscillates in a slot in the bottom of the shuttle box as the shuttle is picked 30 into and out of the box. When the shuttle is at rest in the shuttle box as shown on Fig. 2, the picker stick is at the outer end of the slot and rests against a buffer pad in the outer end of the slot. The pad may comprise a lay end strap 12 35 made of leather or other suitable material. A padding 13 made of leather or other suitable material is placed beneath the strap 12. The position of the picker stick and thereby of the picker is adjusted by increasing or decreasing the thickness of the padding.

When a call for replenishment of filling has 40 been made by the filling feeler mechanism, not shown, the shuttle feeler 4 is raised to "feeling" position to "feel" the shuttle as the lay moves forwardly to see if it is properly boxed. If the shuttle is not properly boxed, that is if the feeler contacts the shuttle and cannot push it into proper position in the box, the feeler revokes the call for transfer and no transfer takes place. 45 When the shuttle is properly boxed the spur of the shuttle should move past the shuttle feeler with a slight clearance therebetween.

In the proper operation of the loom the shuttle feeler should clear the spur of the shuttle when 50 the shuttle is properly boxed for transfer and means are provided for adjusting the position of the shuttle feeler to give this clearance.

The means for adjusting the shuttle feeler may 55 comprise a pair of spaced fitting strips 14—15 on the shuttle feeler tip 16 at the junction of the

tip with the shuttle feeler arm 17. The clearance between the shuttle feeler and the spur 10 of the shuttle may be adjusted by filing either strip 14 or 15. In addition to this means of adjustment, the bracket (not shown) by which the shuttle feeler is mounted on the loom frame may be provided with fitting strips.

From the foregoing it is seen that for proper adjustment of the picker stick and shuttle feeler the shuttle must first be properly positioned in the shuttle box in relation to the magazine.

To properly position the shuttle relative to the magazine for transfer gauge means are provided. Such gauge means may comprise a male and a female gauge member.

The male gauge member may comprise a spindle 18 of the same length as that of the filling carriers used in the loom. The spindle 18 may be made of wood or metal or any other suitable material and has at one end an enlarged cylindrical head or butt 19. The head 19 is of the same size as the heads of the filling carriers used in the loom and may be provided with a plurality of raised spaced ribs or rings 20. The head 19 may be formed integral with the spindle 18 or may be a separate member fixedly mounted thereon. The rings 20 may be metallic rings mounted on the head or projecting ribs formed integral therewith. The spindle 18 is provided with indicating means located at a predetermined distance from the head 19. The indicating means may comprise a laterally extending projection or abutment 21. The projection 21 may be formed integral with the spindle 18 or as a separate member fixedly attached thereto. The projection 21 has a rounded free end 22 provided with flat parallel machined sides for a purpose later to be described.

The female gauge member may comprise a spindle 23 made of wood or metal or any other suitable material. The spindle 23 has at one end an enlarged cylindrical head or butt 24. The head 24 is of the same size as the head of the filling carriers used in the loom and is provided with a plurality of raised spaced ribs or rings 25. The head 24 may be formed integral with the spindle 23 or may be a separate member fixedly mounted thereon. The rings 25 may be metallic rings mounted on the head or projecting ribs formed integral therewith. The spindle 23 is provided with indicating means located at a predetermined distance from the head 24. The indicating means may comprise a laterally extending projection or abutment 26. The projection 26 may be formed integral with the spindle 23 or as a separate member fixedly attached thereto. The outer end of the projection 26 is provided with a recess 27, having parallel machined side walls, for the reception of the free end 22 of projection 21.

The shuttle position gauge of my invention is adapted to be used with any type of magazine in which a reserve supply of filling carriers are maintained and in which each carrier is successively brought into a position over the shuttle for transfer by a transfferer. The particular magazine shown on the drawing is of the rotary battery type and includes a transfferer 28, a disc 29 provided with spaced circumferential pockets 30 for reception of the bobbin butts, and a disc 31 provided with spaced circumferential pockets 32 for the reception of the bobbin tips. The pockets 32 may be mounted on disc 31 and spring 33 may be employed to permit resilient movement between the disc and the pockets.

As shown on Fig. 2 the male member is placed in the battery in the position ordinarily occupied by a bobbin when in transfer position. The female member is placed in the shuttle in the position ordinarily occupied by the bobbin with the head engaged by the bobbin gripping spring, then by moving the shuttle in the shuttle box until the male projection 22 fits into the recess 27 of the female projection 26 the shuttle is brought into proper position relative to the battery and transfferer for transfer.

A new and successful method of adjusting the position of the picker stick and the shuttle feeler may be followed by using the shuttle positioning gauges of this invention.

Such method may comprise the steps of first positioning the shuttle in proper operative relation to the magazine by moving the lay to the front center, then mounting the male gauge in the magazine and the female gauge in the shuttle and then aligning the projections of the two gauges, then positively locking the shuttle in the adjusted position by engaging the projection of the male member in the recessed projection of the female member; then while the shuttle is locked so adjusting the picker that it firmly engages the spur of the shuttle by increasing or decreasing the amount of padding beneath the lay end strap and then adjusting the shuttle feeler so that there will be a slight clearance between the spur of the shuttle and the shuttle feeler.

After boxing the shuttle as described above the shuttle running normally will show a clearance between the shuttle spur and shuttle feeler and when the shuttle is stopped for transfer it will be properly positioned relative to the magazine for transfer.

Another modification of the gauge member is shown in Figs. 4 and 6. The gauge as shown in this modification may comprise a spindle 34 made of wood or metal or any other suitable material. The spindle 34 has at one end an enlarged cylindrical head or butt 35. The head 35 is of the same size as the heads of the filling carriers used in the loom and is provided with a plurality of raised spaced ribs or rings 36. The head 35 may be formed integral with the spindle 34 or may be a separate member fixedly mounted thereon. The rings 36 may be metallic rings mounted on the head or projecting ribs formed integral therewith. The other end of spindle 34 extends upwardly and forwardly over the head 35 as seen on Fig. 6. The extreme end 37 being in substantially the same vertical plane as the head 35.

As shown on Fig. 4 the gauge is placed in the shuttle with the head 35 engaged by the bobbin engaging spring 11. Then the shuttle is moved in the shuttle box until the end 37 abuts the rear wall of the pocket 30. When in this position the shuttle is properly positioned relative to the magazine for transfer and is locked against longitudinal motion inwardly of the lay.

The modification of the gauge as shown on Figs. 5 and 7 may comprise a spindle 38 made of wood or metal or any other suitable material. The spindle 38 has at one end an enlarged cylindrical head or butt 39. The head 39 is of the same size as the head of the filling carriers used in the loom. The head 39 may be formed integral with the spindle 38 or may be a separate member fixedly mounted thereon. The spindle 38 is provided with a marker or indicating means located at a predetermined distance from the head 39. The indicating means may comprise a

laterally extending projection 40. The projection 40 may be formed integral with the spindle 38 or as a separate member fixedly mounted thereon. Projection 40 extends laterally from spindle 38 then extends substantially parallel therewith in a direction towards the head 39. The free end of the projection 40 forms an abutment 41 lying in substantially the same vertical plane as the head 39.

As shown on Fig. 5 spindle 38 is mounted in the battery in the position ordinarily occupied by a bobbin when in transfer position. When in this position the projection 40 will extend into the shuttle in the opening therein ordinarily occupied by a bobbin. By moving the shuttle in the shuttle box until the free end or abutment 41 of the projection 40 engages the cover 42 of the spring 11 in the shuttle, the shuttle is brought into proper operative position relative to the magazine for transfer. With the shuttle properly positioned relative to the magazine, the picker stick and shuttle feeler may be adjusted in the manner previously described.

When using the modifications shown in Figs. 6 and 7 the method of adjusting the picker stick and shuttle feeler as set forth above may be followed. However the gauges shown in Figs. 6 and 7 provide for locking the shuttle against longitudinal movement in one direction only. In the modification shown in Fig. 7, however, the projection 40 may be provided with a head adapted to engage the bobbin engaging spring in the shuttle and thereby positively lock the shuttle.

Having thus fully disclosed the preferred embodiments of my invention, I claim:

1. A gauge for positioning the shuttle of the usual automatic filling replenishing loom relative to the magazine thereof, said gauge comprising means in said shuttle forming an abutment, a member adapted to be mounted in said magazine and means carried by said member for engaging said abutment and thereby holding said shuttle in operative position relative to said magazine.

2. A gauge for positioning the shuttle of an automatic filling replenishing loom relative to the magazine thereof, said gauge comprising means in the magazine forming an abutment, a member adapted to be mounted in said shuttle and means carried by said member for engaging said abutment and thereby holding said shuttle in operative position relative to said magazine.

3. A gauge for positioning the shuttle of the usual automatic filling replenishing loom relative to the magazine thereof, said gauge comprising a member adapted to be mounted in said shuttle, a second member adapted to be mounted in said magazine, and cooperating indicating means carried by said members for indicating operative position of said shuttle to said magazine.

4. A gauge for positioning the shuttle of the usual automatic filling replenishing loom relative to the magazine thereof, said gauge comprising a member adapted to be mounted in said shuttle, a second member adapted to be mounted in said magazine, and cooperating interlocking means carried by said members for locking said shuttle in operative position relative to said magazine.

5. A shuttle position gauge comprising a pair of spindles, each of said spindles having an enlarged head on one end and indicating means fixed thereon at a predetermined distance from said head, each of said heads having a plurality of spaced ribs thereon.

6. A shuttle position gauge comprising a male member and a female member, said male mem-

ber including a spindle having an enlarged cylindrical head on one end, and a laterally extending projection fixedly attached to said spindle at a predetermined distance from said head, said female member including a spindle having an enlarged cylindrical head on one end, said last named head having a plurality of spaced metallic rings mounted thereon and a laterally extending recessed projection fixedly attached to said last named spindle at a predetermined distance from the head thereof, said recessed projection being adapted to receive said first named projection.

7. A gauge for positioning the shuttle of an automatic replenishing loom of the type including a shuttle box and magazine adapted to hold a plurality of filling carriers and move them successively to transfer position, said gauge comprising a pair of complementary members, each of said members having a projection extending laterally therefrom, one of said members being adapted to be mounted in said magazine in transfer position and the other of said members being adapted to be mounted in said shuttle, whereby upon movement of said shuttle in said shuttle box to bring said projections into alignment said shuttle will be properly positioned relative to said magazine for transfer.

8. A gauge for positioning the shuttle of an automatic replenishing loom of the type including a shuttle box and a magazine adapted to hold a plurality of filling carriers and move them successively into transfer position, said gauge comprising a pair of complementary members, each of said members having a laterally extending projection, one of said projections having a recess therein adapted to receive the other projection, one of said members being adapted to be mounted in said magazine in transfer position and the other of said members being adapted to be mounted in the shuttle whereby upon movement of the shuttle in said shuttle box to bring said projections into engagement said shuttle will be properly positioned relative to said magazine for transfer.

9. A gauge for positioning the shuttle of a bobbin changing loom of the type including a shuttle box and a battery adapted to hold a plurality of bobbins and move them successively into transfer position, said gauge comprising a pair of complementary members, one of said members including a spindle having a butt and a tip and a laterally extending projection secured thereto at a predetermined distance from said butt, said member being adapted to be mounted in said battery in transfer position, the other of said members including a spindle having a butt at one end and a laterally extending projection at the other end, said last named projection having a recess for the reception of said first named projection, said second named member being adapted to be mounted in said shuttle whereby upon placing said shuttle in said shuttle box beneath said battery and engaging said projections said shuttle will be in proper position for transfer.

10. A gauge for positioning the shuttle in a bobbin changing loom of the type including a shuttle having a bobbin holding spring therein, a shuttle box and a rotary battery adapted to hold a plurality of bobbins and move them successively into transfer position, said gauge comprising a male member and a female member, said male member including a spindle having at one end an enlarged cylindrical head and at a predetermined distance from said head a laterally extending projection, said male member

being adapted to be mounted in said battery in transfer position, said female member including a spindle having a laterally extending recessed projection on one end and on the other end an enlarged cylindrical head provided with a plurality of spaced ribs, said female member being adapted to be mounted in said shuttle with the ribbed head of said female member held by the bobbin holding spring of the shuttle, whereby upon moving said shuttle in the shuttle box 10 until said projection carried by said male member is received in the recessed projection of said female member said shuttle will be properly positioned relative to said battery for transfer.

11. The method of adjusting the position of the picker stick of the usual automatic filling replenishing loom having a picker, shuttle and magazine, comprising the steps of first positioning the shuttle in proper operative relation to the magazine, then positively locking the shuttle in said position, and then while the shuttle is locked, so adjusting the picker that the latter engages the shuttle.

12. The method of adjusting the positions of the picker stick and the shuttle feeler of the usual automatic filling replenishing loom having a picker, shuttle and magazine, comprising the steps of first positioning the shuttle in proper operative relation to the magazine, then positively locking the shuttle in said position, then while the shuttle is so locked adjusting the picker so that the latter engages the shuttle and then so adjusting the shuttle feeler that there is a slight clearance between the side thereof and the spur of the shuttle.

13. The method of adjusting the position of the picker stick of the usual automatic filling replenishing loom having a picker, shuttle and magazine, comprising the steps of first positioning the shuttle in proper operative relation to the magazine by mounting in the one a member carrying means arranged to engage an abutment on a member carried by the other when the shuttle is in proper operative position, and then so adjusting the picker that the latter engages the shuttle.

14. The method of adjusting the position of the picker stick of the usual automatic filling replenishing loom having a picker, shuttle and magazine, comprising the steps of first positioning the shuttle in the proper operative relation to the magazine by aligning a marker on the shuttle with a marker on the magazine, then positively locking the shuttle in said position from movement in one longitudinal direction, and then while the shuttle is locked, so adjusting the picker that the latter engages the shuttle.

15. The method of adjusting the position of the picker stick of the usual automatic filling replenishing loom having a picker, shuttle and magazine, comprising the steps of first positioning the shuttle in proper operative relation to the magazine by mounting in the magazine a member carrying means arranged to engage an abutment on the shuttle when the shuttle is properly positioned, and then while the shuttle is in proper position, so adjusting the picker that the latter engages the shuttle.

16. The method of adjusting the position of the picker stick of the usual automatic filling replenishing loom having a picker, shuttle and magazine, comprising the steps of first positioning the shuttle in proper operating relation to the

magazine, then positively locking the shuttle in said position from movement in one longitudinal direction by mounting in the shuttle a member having locking means adapted to engage a part carried by the magazine and so lock the shuttle when the shuttle is in said position, and then while the shuttle is so locked so adjusting the picker that the latter engages the shuttle.

17. The method of adjusting the position of the picker stick of the usual automatic filling replenishing loom having a picker, shuttle and magazine, comprising the steps of first positioning the shuttle in proper operative position relative to the magazine, then positively locking the shuttle in said position from movement in one longitudinal direction by mounting in the magazine a member carrying locking means adapted to engage the shuttle and so lock the shuttle when the shuttle is in said position, and then while the shuttle is so locked, so adjusting the picker that the latter engages the shuttle.

18. The method of adjusting the position of the picker stick of the usual automatic filling replenishing loom having a picker, shuttle and magazine, comprising the steps of first positioning the shuttle in proper operative position relative to the magazine, then positively locking the shuttle while in said position by engaging complementary locking means mounted on the shuttle and magazine, and then while the shuttle is locked, so adjusting the picker that the latter engages the shuttle.

19. A method of adjusting the position of the picker stick and shuttle feeler of a bobbin changing loom so that the shuttle will be properly positioned for transfer, comprising the steps of moving the lay to front center, mounting in the battery in the position normally occupied by the bobbin when in transfer position a gauge member having a depending projection, mounting in the shuttle a gauge member having an upstanding recessed projection, moving the shuttle in the shuttle box until the depending projection is engaged in the recessed projection, adjusting the thickness of the padding in the outer end of the slot in the bottom of the shuttle box until the picker on the picker stick is firmly pressed against the outer spur of the shuttle and then adjusting the shuttle feeler by filing the fitting strips until there is a slight clearance between the side of the feeler and the inner spur of the shuttle.

20. The method of adjusting the position of the picker stick of the usual automatic filling replenishing loom having a picker, shuttle and magazine, comprising the steps of first positioning the shuttle in proper operative relation to the magazine by mounting in the shuttle a member carrying means arranged to engage an abutment on the magazine when the shuttle is properly positioned, and then while the shuttle is in proper position, so adjusting the picker that the latter engages the shuttle.

21. A gauge for positioning a shuttle member relative to a magazine member in an automatic filling replenishing loom, said gauge comprising means carried by one of said members forming an abutment, an element arranged to be mounted in the other of said members, and means carried by said element for engaging said abutment whereby the shuttle is restrained from movement out of operative position relative to said magazine.

HAROLD HOEBER.
